REINFORCED SHOPPING BAG

Filed Dec. 12, 1933

2 Sheets-Sheet 2

Inventor

H. E. Musick

Watson E. Coleman

Attorney

(see Figure 2) the ends of this cord extending upward of each end of the bag and being sewed or otherwise engaged therewith at 23 (see Figure 1). The lining 12 of the bag may be, and preferably is, folded over at the top of the bag, as shown in Figure 6 at 24.

It will be seen that the bag constructed in this manner may be folded upon the lines of the panels, as shown in Figure 7, and that such a bag may 10 be readily inserted within a sheath or carrying case, such as illustrated in Figure 8 and designated 26, this carrying case being of any suitable fabric, being rectangular in cross section and closed at its 15 upper end by a foldable flap 27 and having a handle 28 whereby it may be carried, thus providing a very convenient way for the carriage of the bag. It will be seen that this bag is thoroughly 20 reinforced and supported so that it will wear a long time and will carry a comparatively heavy 25 weight of goods. While I have shown two carrying cords provided with handles, yet it will be obvious that other supporting cords may be provided 30 extending longitudinally of the bag and engaging therewith between the joints of the sections or panels without departing from the spirit 35 of the invention. Thus the bag may be reinforced to any desired extent. The bottom of the bag may be made of any suitable materials for this purpose although preferably a textile fabric is used. By providing eyes 19 for the cords 20, these 40 cords cannot get out of place, sag or tend to shift. As is the case with the ordinary shopping bag, the cords may shift longitudinally and thus one handle be longer than the other handle, making it necessary to adjust the cords.

While preferably I use thin sheet metal for the purpose of forming the reenforcing strips 13, I do not wish to be limited to this as other relatively 45 rigid material might be used for the purpose, such as heavy and tough paper or cardboard.

While I have illustrated certain details of construction and arrangement of parts, I do not wish to be limited thereto as obvious changes may be made therein without changing the spirit of the 50 invention as defined in the appended claims.

I claim:

1. A shopping bag composed of longitudinally 55 extending rigid panels foldably connected to each other between the panels, a bottom of flexible fabric, and supporting cords extending across the bottom and up on opposite sides thereof, the cords being disposed in line with the folds between the panels.

2. A shopping bag composed of longitudinally 60 extending fabric panels foldably connected to each other between the panels, and a bottom of flexible fabric, substantially rigid reenforcing elements disposed longitudinally of the panels and between the hinged connection of the panels to each other, and supporting cords extending across the bottom and up on opposite sides and having handles and eyes attached to the sides of the bag and through which the cords pass.

3. A shopping bag composed of an inner lining 65 of woven fabric, a plurality of longitudinally extending substantially rigid, stiff reenforcing elements operatively attached to the lining and extending longitudinally of and for the entire length of the bag, said reenforcing elements being spaced from each other to permit the fabric between the reenforcing elements to fold.

4. A shopping bag including a lining of woven 70 fabric having a flexible bottom, longitudinally extending reenforcing elements of substantially rigid and stiff material extending from top to

bottom of the bag, said reenforcing elements being spaced from each other to permit the bag to flex between the reenforcing elements, cords extending longitudinally of the bag, the reenforcing elements being formed at their ends to embrace the cords, and flexible reenforcing strips of textile fabric extending longitudinally of the bag between the reenforcing elements and overlying said cords.

5. A shopping bag including a body of woven fabric having a flexible bottom, longitudinally extending reenforcing elements of substantially stiff and rigid material extending from top to bottom of the bag, said reenforcing elements being spaced from each other to permit the bag to flex between the reenforcing elements, cords extending longitudinally of the bag, the reenforcing elements being formed at intervals to embrace the cords, and flexible reenforcing strips of textile fabric extending longitudinally of the bag between the reenforcing elements and overlying said cords, certain of the cords being extended and having carrying handles.

6. A shopping bag of the character described composed of a body of woven fabric, substantially rigid reenforcing elements extending the full length of the bag and dividing the bag into vertical stiff panels but spaced from each other whereby the material of the bag between the reenforcing elements is flexible to permit the panels to be folded upon each other, the bag being formed of a flexible bottom, and cords extending vertically of the bag, there being a pair of cords between each pair of reenforcing elements, the cords being operatively connected to the reenforcing elements, strips extending across the outer face of the bag, disposed between the reenforcing strips and stitched to the face of the bag on each side of the pair of cords, and oppositely disposed pairs of carrying cords extending across the bottom of the bag and up opposite sides thereof and provided with handles, and eyes connecting said cords to the body of the bag.

7. A shopping bag of the character described composed of longitudinally extending panels of woven fabric, substantially rigid reenforcing elements extending the full length of each panel but spaced from each other whereby the material of the bag between the reenforcing elements is flexible to permit the panels to be folded upon each other, the bag having a flexible bottom, cords extending vertically of the bag there being a pair of cords between each pair of reenforcing elements, the cords being operatively connected to the reenforcing elements, and fabric strips extending over the outer face of the bag between the reenforcing strips and embracing said last named cords, and oppositely disposed pairs of carrying cords extending across the bottom of the bag and up opposite sides thereof and provided with handles, outwardly projecting eyes connecting said cords to the body of the bag, and a cord extending across the bottom of the bag transverse to the carrying cords and extending up opposite sides of the bag between two of the panels and being operatively engaged with the side of the bag.

8. A shopping bag composed of an inner lining of flexible textile fabric, a plurality of vertically disposed sheet metal reenforcing elements extending the full length of the bag and having cross bars at intervals, the cross bars being bent to form beads, cords extending up through the beads, strips of fabric extending upward over the spaces between the cross bars of the reenforc-

ing elements and stitched to the lining to embrace the cords whereby the bag is formed of a plurality of relatively stiff vertically extending panels connected by flexible portions permitting the panels to be folded one upon the other, and carrying cords extending across the bottom and upward on opposite sides of the bag, the carrying cords being disposed over the middle portions of said strips, the carrying cords at their upper ends

having handles and clips inserted through the strips and lining and clinched thereto and formed to provide eyes through which the carrying cords pass and cords reenforcing the bottom of the bag and extending at right angles to the carrying cords and upward on each side of the bag and being stitched thereto. 5

HARRY F. MUSICK.
